SWITCH

Elwood T. Platz, Detroit, Mich., assignor to Bulldog Electric Products Company, Detroit, Mich., a corporation of West Virginia

Original application August 27, 1942, Serial No. 456,305. Divided and this application February 6, 1943, Serial No. 474,929

1 Claim. (Cl. 200—116)

This application relates to switches, and is a division of my prior application, Serial No. 456,305, filed August 27, 1942.

This application discloses a switch whose actuation is accomplished by means of an actuator which is given exactly the same movements for all operations. The actuator is shown as a push button, pushed in manually and spring pressed outwardly when released. It might also be an armature or a solenoid of a magnet, etc., the fact that it is a reciprocator suggesting other operating means for the actuator.

The operative connection between the actuator and the contactor is of such a form that successive identical manipulations of the actuator cause different results. One manipulation of the actuator may cause circuit opening. A successive manipulation, exactly the same as the first, may however, cause circuit closing. A third may cause latch resetting in the event the switch has a releasable latch, as is true of the switches here shown.

The difference in result is obtained through the use of a selector mechanism responsive to the condition of the switch parts and determining the effect of actuator manipulation on the switch parts.

One form of such switch is here illustrated and will now be described upon reference to the appended drawing.

In the drawing,

Figs. 1-3 are three different positions views of that form of switch.

Fig. 4 is a section on line 4—4 of Fig. 2.

The drawing shows an embodiment employing push button operation for a switch having a contactor 210 latched at 211 by a bimetal strip 212, and having a contact end 213, and being biased upwardly by a compression spring 214.

A push button 230 mounted to slide in the casing is spring pressed outwardly by a spring 231 and is integral with a slotted link 232, pivotally connected at 233 to the contactor 210. Pivotally mounted on the link 232, at 234, is a selector finger 235, adapted to cooperate with high and low stops 236 and 237 of a rocker 238, pivotally mounted on the casing by means of pivot 239, cleared by the slot 239a of link 232, such slot also insuring rectilinear movement of link 232 on pivot pin 239. Stops 236—237 are separated by a hump 240, and also are at different levels with respect to the stationary contact 241. Stops 241a are also provided to determine positions of rocker 238.

In the position of the parts that is shown in

Fig. 2, the circuit is closed, with latch 212 holding arm 210 at 211 as a pivot, and selector finger is on the left side of the selector hump 240 in high stop 236. When the push button 230 is pushed down, its link 232 moved downwardly and selector finger 235 also moves downwardly, to leave rocker 238 and to engage the left-hand one of the two stops 242. This rocks the selector finger to the center position. When the button is released, spring 231 will move it and the selector finger upwardly and this will position the selector finger in low stop 237, leaving the contactor in the open circuit position, inasmuch as stop 237 is well below stop 236. Rocker 238 will have been rocked to the opposite one of its two positions so that when the push button 230 is pushed down again, the parts will go through the reverse motion and come to rest with finger 235 in high stop 236, as now shown.

The two different levels of stops 236—237 determine two different positions of the selector finger and, thus, two different positions of the contact 213 for open and closed circuit.

The foregoing is the manual switching action with the latch holding arm 210. The latch mechanism comprises a bi-metallic strip 212 which is secured at its upper end, but which is free to move at its lower end. This strip normally extends in a flat vertical plane as shown in Fig. 2, but when the bi-metallic strip moves to the left, the arm 210 is free to move upwardly. When the latch is in the position shown in Fig. 2, the arm 210 is held so as to pivot about the lower end of the strip 212. Thus it will be seen that oscillation of the lower end of the bi-metallic strip provides a latching mechanism for the arm 210.

On release of latch 212 at 211, spring 214 rocks arm 210 on pivot 233 as an axis to open the circuit, parts 230, 232, 234, 238 remaining in closed circuit position, with stop 242a stopping the arm 210. If the button 230 is then pushed down, contactor 210 will be rocked on relatching stop 243 and relatched but all the parts will be in open circuit position. Manual switching action may take place thereafter through manipulation of button 230.

Now having described the switch herein illustrated, reference should be had to the claim which follows.

I claim:

In a switch, the combination of an actuated part in the form of a contactor, a push button operatively connected thereto at a point intermediate its ends which is pushed in and then

released for each operation, latch means releasably holding one end of the contactor, a stationary contact adapted to be engaged by the other end of the contactor, spring means intermediate the ends of the contactor for biasing it to move to open circuit position on latch release, the spring means biasing the contactor towards closed circuit position when the latch holds, the latch means being relatched when the push button is pushed in after contactor movement following latch release, a selector mechanism controlled by the push button for operatively connecting the push button to the contactor in such a manner that successive push-in movements of the push button provide successively different ones of two different rest positions of the contactor, closed circuit and open circuit, whereby successive identical push-in movements of the push button will cause the contactor to move to

and stop in successively different positions, closed circuit and open circuit, respectively, the spring means moving the contactor towards closed circuit position when the latch holds, except as inhibited by the selector having previously defined an open circuit position therefor, and moving the contactor into closed circuit position when the selector is moved to permit such movement of the contactor, and moving the contactor to open circuit position when it is unlatched, the selector mechanism providing a pivotal support for the contactor during its spring caused movement after latch release, the latch means also providing a pivotal support for the contactor during certain of its movements, and a stop for providing a pivot for the contactor during its relatching movement.

ELWOOD T. PLATZ.
